H. J. Gwyer,
REFRIGERATOR CONSTRUCTION,
APPLICATION FILED APR. 28, 1916.

1,266,794.

Patented May 21, 1918.

UNITED STATES PATENT OFFICE.

HERBERT JUBE GWYER, OF NEW YORK, N. Y.

REFRIGERATOR CONSTRUCTION.

1,266,794.

Specification of Letters Patent. Patented May 21, 1918.

Application filed April 28, 1916. Serial No. 94,110.

To all whom it may concern:

Be it known that I, HERBERT J. GWYER, a citizen of the United States of America, residing at New York city, New York, have 5 invented a new and useful Refrigerator Construction, of which the following is a specification.

My invention relates to an improved refrigerator construction and aims more particularly at improving the frame thereof whereby such parts may be standardized. By standardizing such parts, great economy is effected in the manufacture of such goods. While I have shown my invention as applied to one form of refrigerator obviously the same may be modified in a variety of ways.

In the drawings:

Figure 1 is a front elevation on a small 20 scale of a refrigerator constructed to embody my invention.

Fig. 2 is a plan view thereof.

Fig. 3 is a view of a short section of a framing piece, relatively enlarged.

25 Fig. 4 is a section on the line 4—4 of Fig. 1.

Fig. 5 is a perspective view of a modification.

Fig. 6 is a view of the underside of 30 Fig. 1.

Fig. 7 is a section of a modification.

In building the frame of the refrigerator, I employ preferably at all corners strips of molding forming framing pieces 35 shaped substantially as shown in Fig. 3, that is to say, the two outer sides of the strip are smooth and arranged at right angles to each other, the other two sides are grooved longitudinally with the desired

40 number of grooves. The corner between the two grooved sides is cut back or beveled, forming in effect a dove-tailed piece at what is the inside corner of the framing piece, this being advantageous for the purpose

45 later seen. In forming the frame the four upright corner pieces 1, 2, 3, 4 will first be suitably secured together with the beveled corners arranged to face inwardly. If desired, the top of the case may then be

50 formed of the four pieces 5, 6, 7 and 8, the corners being properly mitered and united by any suitable fastening means such as the fasteners 9—9. In forming the top, the lining member 10 may be inserted into the 55 grooves of the aforesaid pieces, as best seen in Fig. 1. The sides and back may receive

lining pieces as indicated at 11, 12, 13, these lining pieces sliding into the grooves in the upright corner pieces. The bottom is formed like the top and is provided with 60 the lower or bottom lining 14. The legs of the refrigerator are indicated at 15—15 and the corners of the bottom frame are cut away as indicated in Fig. 6 to afford clearance for the legs. The legs are formed 65 by the solid ungrooved parts of the lower ends of the upright members 1, 2, 3 and 4, the grooved portions and the dove-tailed corner pieces being trimmed off as shown in Figs. 1 and 6. This permits the lower 70 panel or frame to be pushed into place between the legs and properly secured. The frame-work thus constructed with the top, bottom, side and rear lining members in place is then ready to receive the finishing 75 work which may comprise filling in the panels on the outside. These panels may be formed of any suitable insulating compound or material such as indicated at 80 16—16.

This insulating material may be held in place in any suitable way. When a second set of grooves is present, this material may project into and be locked in said grooves.

In the drawings I have shown the framing strip provided with two sets of grooves, for example, 17—18 indicate the inner set and 19—20 the outer set (see Fig. 3). The outer set 19—20 are useful for various purposes, for example, a second lining piece 90 might be slid into place, in which event there would be two linings with an air space between them, as indicated in the detail view, Fig. 7, the two linings therein shown being indicated at 21—22. 95

The dove-tailed inner corner of each framing piece provides a beveled filler at each inner corner of the refrigerator, as indicated at 23—24—25, Fig. 1, and at 26, 27, 28 and 29, Fig. 4. If desired, the dove-tailed corner piece may be provided with a metallic covering as indicated at 30, Fig. 5, it being desirable in high grade boxes to avoid as far as possible the exposure of wood within the refrigerator. 100

It should be understood that the box as illustrated may be, if desired, covered with any suitable sheet metal, or might be finished in any desired way.

In some constructions it may be desirable 110 to introduce at intervals cross braces between the framing pieces, such cross braces

may be provided with tongues adapted to project into the outer grooves. Such braces are indicated at 31—31.

What I claim is:

- 5 1. In a refrigerator construction, a frame forming the main skeleton of said refrigerator and comprising integral supporting members suitably connected, said members having therein inner and outer longitudinal grooves in each of two adjacent sides, a sanitary lining member projecting into and held by the walls of a plurality of said inner grooves, and a panel member of different material projecting into and held by the walls of a plurality of said outer grooves, said lining and panel member being held against displacement by those parts of the frame engaging the same, said members being inserted in said grooves before the 10 frame members are completely assembled, and a beveled corner portion between the inner lining receiving grooves on certain of said frame members, and a metal covering for said beveled corner portion, the edges
- 15
- 20

of said metal covering extending into said inner grooves to hold said metal covering in place.

2. In a refrigerator construction, a frame forming the main skeleton of said refrigerator comprising integral supporting members suitably connected, said members having therein inner and outer longitudinal grooves in each of two adjacent sides, a sanitary lining member retained entirely by said inner groove and a heat insulating panel member of different material retained by said outer groove, said lining and panel member being retained in the respective grooves of said integral members independent of any other holding means, said lining member being inserted in said inner groove before said frame members are completely assembled, and a beveled corner portion between said inner lining receiving grooves, a metal covering for said corner, the edges of 30 35 40 45 said metal covering being held in the same groove as said inner lining member.

HERBERT JUBE GWYER.
